[57] CLAIM

The ornamental design for rail element for a toy railway, as shown and described.

DESCRIPTION

FIG. 1 is a perspective view of a rail element for a toy railway showing my new design;

FIG. 2 is a bottom perspective view thereof;

FIG. 3 is a top perspective view of a modified embodiment of the design shown in FIGS. 1 and 2; and

FIG. 4 is a bottom perspective view thereof.

FIG. 1

FIG. 2

FIG. 3

FIG. 4
